CHANGEABLE ADVERTISING EXHIBITOR

Albert John Kauffman, New York, N. Y.

Application February 11, 1933, Serial No. 656,349

7 Claims. (Cl. 40—36)

The present invention on changeable advertising exhibitors is designed as an improvement over my co-pending application, Serial Number 579,273, filed December 5th, 1931, and is intended 5 to greatly increase the operating efficiency of the machine.

In the present improvement I have, as an object of the invention, the employment of safety switches in the exhibitor which automatically 10 function to stop operation of the latter on the failure of the cards to properly feed.

The invention further contemplates the following objects: to provide improved plate impinging abutments; to provide silencers for the abutments, thereby permitting noiseless transfer of the cards in the exhibitor; to construct the exhibitor frame in a manner which permits removal of the cards from and insertion of the cards in the exhibitor in a more facile and expeditious manner; 20 to equip the card carrying carriage with dogs of improved design, the dogs being also articulate for convenience in removing or inserting the cards; to mount yieldable card stops in the terminals of the exhibitor and to provide an adjustable motor to take up the slack in the operating chain if and when this becomes necessary.

Other objects of this invention will be apparent from the following description of the present preferred form thereof, taken in connection with the 30 accompanying drawings, wherein

Fig. 1 is a perspective view of an improved changeable exhibitor constructed in accordance with the present invention;

Fig. 2 is a vertical longitudinal sectional view 35 of the exhibitor, showing parts thereof broken away;

Fig. 3 is a horizontal longitudinal sectional view, with portions of the bases of the exhibitor frame broken away;

Fig. 4 is a cross-sectional view, taken on the line 4—4 of Fig. 3, looking in the direction of the arrow, showing to advantage the manner of mounting the card abutments in the exhibitor frame;

Fig. 5 is a detail, fragmentary sectional view, taken on the line 5—5 of Fig. 2, looking in the direction of the arrow, showing to advantage the relationship of the card abutments to the silencers therefor;

Fig. 6 is a similar view, taken on the line 6—6 of Fig. 2, showing the plate abutments and the lugs struck out therefrom;

Fig. 7 is a perspective view of one of the plate abutments and pintle, the latter being shown separate from the abutment;

Fig. 8 is a detail, enlarged, fragmentary vertical sectional view, taken through the frame immediately above the motor containing portion of the base thereof and showing to advantage one of the safety switches with the means employed for operating the same;

Fig. 9 is a horizontal sectional view through the top of the exhibitor, showing the guide rail for the advertising cards in top plan;

Fig. 10 is a perspective view of one of the yieldable card stops used on the guide rail;

Fig. 11 is a perspective view of the carriage plunger used for operating the safety switch;

Fig. 12 is a detail, fragmentary perspective view of the carriage for the advertising cards, showing 70 one of the dogs engaged therewith; and

Fig. 13 is a detail, fragmentary vertical sectional view of the carriage and hinged dog.

In the drawings, the exhibitor frame of the present invention is generally designated 14 and consists in the present instance of a pair of bases 15, of truncated pyramidal shape, which support a rectangular superstructure 16. The bases 15 are hollow, adapted for the reception of operating mechanism, as hereinafter set forth. The superstructure 16 is composed of a hollow base bar 17, a top bar 18 and hollow end stays 19. The superstructure is of skeleton design, open on both sides, so that advertising matter may be simultaneously exhibited on both sides of the frame in a manner hereinafter set out. Mounted for movement in the base bar 17 is an endless chain 20 trained over sprockets, the shaft 21 of one of which is journaled through the floor of the base bar 17, the shaft 22 of the other sprocket also depending through the floor of the base bar into operative engagement with a motor 23. The motor is adjustably mounted through the means of bolts 24, on the floor of the base bar 17, within the confines 95 of one of the bases 15. The bolts 24 are adjustably mounted in elongated openings 25, permitting the motor to be adjusted for taking up slack in the sprocket chain.

The sprocket chain 20 is equipped with a roller 100 pin 26, the latter being engaged for movement in an elongated recess formed in a bearing block 27, mounted on a carriage 28. The carriage is U-shaped in cross-section, the sides thereof being spaced from and embracing an inverted U-shaped base 29, pendently carried by a supporting platform 30, the latter being U-shaped in cross-section and adapted for the reception of indicia bearing cards 31. The sides of the carriage 28 and base 29 are complementary formed to receive 110

therebetween anti-friction means 32, as shown to advantage in Fig. 4 of the drawings. At each end of the carriage and opposite sides thereof, a spacing block 33 is provided, to which 5 a dog 34 is hingedly engaged. Each of the dogs consists of a plate, one of the lateral margins of which is sleeved over a shaft 35, carried by the spacing block 33. The opposite margin of the plate is bent at right angles to overhang the block 10 33 and lie in parallel relation thereto, providing a flange 36, which tapers outwardly toward its inner end and terminates abruptly, short of the inner end of the plate, in a card engaging shoulder 37. Each of the dogs 34 is normally held in a vertical position, as shown in Figs. 12 and 13, by a spring 38, which is coiled on the shaft 35. Manifestly, the dogs 34 may be moved laterally against the resistance of the springs 38 when it is desired 15 to insert or remove the cards 31.

20 The indicia bearing cards 31 are mounted on the platform 30 between the up-turned sides of the latter and extend upwardly through a longitudinally extending opening in the top of the base bar 17. The upper margins of the cards are embraced by a guide rail 39 which parallels the platform 30 and is secured to the latter by suitable fastening means 40, mounted in the end bars 19. It will be noted that the opposite terminals of the bars 19 abut the inner faces of the platform 30 25 and guide rail 39. The fastening means 40 extends completely through the end bars 19, the lower ends thereof extending through the platform 30, base bar 17 and into the bases 15 for engagement with the latter. The upper ends of 30 the fastening means extend through the guide rail 39 and are secured to the latter. In this manner the entire frame of the exhibitor is detachably engaged in a way to facilitate assemblage of the parts of the frame, yet providing a compact 35 structure, with the cost of manufacture reduced to a minimum.

40 Mounted on the platform 30, approximately midway of the ends of the latter, is a center block 41, which has a pair of pintles 42 mounted therein, the upper ends of the pintles projecting through the guide rail 39 and secured thereto in any suitable manner. Each of the pintles is adapted for engagement with a card abutment 43. In the present instance I prefer to make the abutment from a metal sheet, rolling one margin 45 thereof to provide a sleeve in which the pinte is fitted. It will be noted that the free margin of the sleeve is spaced from the plate body, as indicated at 44, through which the ends of coil 50 springs 45 are free to project into engagement with the faces of the abutments, as shown to advantage in Figs. 4 and 6. Furthermore, this permits of expeditious removal of the springs from 55 the pintles. Preferably a portion of each of the 55 pintles 42 is reduced, as shown at 46, to provide a recess for the springs. The springs normally urge the free margins of the abutment plates 43 outwardly into engagement with the guide rail 39, the latter being equipped with cushions 47, which 60 serve as silencers for the plates. Each of the abutment plates is also provided with a struck out lug or ear 48, which is adapted to impinge against certain of the plates lying on opposite sides of the center block 41, as shown to advantage in Fig. 3, 65 thereby preventing accidental movement of the cards from one part of the exhibitor to the other.

70 If, due to the failure of any part of the mechanism, the continuity of operation of the cards is impaired, I have provided suitable means automatically operated by the advertising matter it-

self, to render the exhibitor inoperative. The means employed for this purpose consists of a plunger 49, mounted in each end of the exhibitor, each of the plungers being slidably engaged in a tube 50, secured to the platform base 29 and mounted within the sides of the latter. One end of each plunger is offset and provided with a right angled head 51, which lies in the path of movement of the cards being transferred, as illustrated to advantage in Fig. 3 of the drawings. Each plunger is further equipped with a switch operating finger 52, which is adapted for engagement with a switch 53, one of said switches being mounted in each end of the base bar 17 in circuit with the motor 23. The opposite end of each plunger projects beyond the inner end of its tube 50 and has a coil spring 54 sleeved thereon, the outer end of the latter abutting a washer 55, which is secured to the plunger by a screw 56, threaded into the bore of the plunger. During the normal operation of the carriage, the extent of movement of the plungers is not sufficient to effect operation of the switches 53. As soon, however, as the plungers are permitted to move in excess of the normal throw of the plungers, the fingers 52 effect movement of the switches 53 with an obvious result.

At each end of the exhibitor I provide card stops, each of which in the present instance, consists of a yieldable plate 57, one end of each of 105 said plates being secured to the guide rail 39 by the fastening means 40. The opposite end of each plate extends through a complementary opening in the guide rail and has its free end looped to reinforce the same for engagement with the 110 plates. These stops are preferably arranged as shown in Fig. 9 of the drawings, to permit clearance of the cards being transferred, and are yieldable to allow the free ends thereof to be removed through the slots in the guide rails when 115 the indicia bearing cards are engaged with, or disengaged from the exhibitor.

In use of the invention, the indicia carrying cards 31 are mounted in groups on the platform 30 in a manner now well known in the art. The plate groups are arranged on opposite sides of the center block 41 and are urged past the latter by the dogs 36 of the carriage when the latter is operated in response to the action of the motor 23. Normally the cards are moved from one 120 group to the other and automatically fed from one side of the exhibitor to the other so that the cards are continuously displayed in succession. As a card is moved longitudinally in the exhibitor from one end of the latter to the other, one of the 125 abutment plates 43 is urged inwardly against the resistance of the spring 45 sufficiently to allow the card to clear. When the moving card arrives at a point in proximity to the terminal of the exhibitor, it is intercepted by the head 51 of the 130 plunger 49 and normally moves the latter against the resistance of the spring 54. The plunger is permitted to move a sufficient distance to allow the card to clear the free margin of the abutment plate, and the latter then flexes inwardly under 135 the influence of its spring. As the sprocket chain 29 continues its movement, pressure on the plate is released thereby permitting the plunger to be retracted and the moving card urged toward the center of the exhibitor into engagement with the struck out lug 48. If for any reason there should 140 be a failure of the abutment plate, on either side of the exhibitor, causing impingement of the card already moved with the card next to be transferred, the plunger 49 moves beyond its safety 145 limit.

zone, thereby effecting contact of the depending finger 52, causing the switch 53 to be operated, thus shutting off the motor. In fact, it is apparent that any movement of the cards which 5 will cause either of the plungers to move in excess of the predetermined limits established therefor, will cause the switches 53 to be thrown, with manifest results. Where there is a normal transfer of a card from one group to the other, the abutment plate 43 which has been urged inwardly, is thrown out against one of the cushions 47, thereby making movement of the abutment noiseless. As illustrated to advantage in Figs. 2 and 9, ample space is provided at the sides of the yieldable plates 57 to permit free transfer of the indicia bearing cards in a manner already described.

In inserting or removing the cards, after the top bar 18 and guide rail 39 have been removed, it is only necessary to urge the dogs 34 laterally 20 against the spring 38. The same springs return the dogs to a normal vertical position as soon as pressure is released therefrom.

Although I have herein described the present preferred form of my invention, it is apparent 25 that various changes may be made in the construction, proportion and arrangement of parts within the scope of the appended claims.

What is claimed is:

1. A changeable exhibitor including a frame, 30 an advertising card supporting carriage mounted on the frame, a motor on the frame in operative connection with the carriage to effect transfer of the cards in the frame, and switches in the frame operable by the cards to render the motor inoperative only when the continuity of feeding the cards is interrupted.

2. A changeable exhibitor including a frame for carrying advertising material, motive means 40 to effect movement of said material in the frame, and means operated by said material, upon dis- placement of the latter, to stop the motive means.

3. A changeable exhibitor including a platform 45 equipped with indicia bearing cards arranged in groups, transfer means for said cards, means on the platform for intercepting a card travelling from one group to the other, and a switch in the exhibitor, in the path of movement of said latter means, operable to stop the transfer means

upon excessive movement of the intercepted card.

4. A changeable exhibitor including a frame, groups of indicia bearing cards arranged in the frame, means for successively transferring said 80 cards from one group to another, abutment plates on the frame between the card groups each of which extends from the top to the bottom of the frame, said plates being movable to permit transfer of the selected card, and means on each of 85 said plates to prevent casual return of the card transferred.

5. A changeable exhibitor including a frame, groups of indicia bearing cards arranged in the frame, means for successively transferring said 90 cards from one group to another, means for intercepting the card transferred, and abutment means mounted between the card groups, said means being movable to permit transfer of the selected card from one group to the other, said 95 intercepting means being yieldable to urge the selected card into engagement with said abutment means upon completion of the transfer of the selected card.

6. A changeable exhibitor including a frame, 100 groups of indicia bearing cards arranged in the frame, means for selectively transferring said cards from one group to another, abutment means mounted on the frame between said card groups, said means being movable inwardly by 105 the selected card being transferred from one group to the other, a spring for urging said means outwardly toward the side of the frame, and silencers on the frame in the path of movement of said means to absorb noise and prevent con- 110 tact of the means with the frame.

7. A changeable exhibitor including a frame, a platform in the frame equipped with groups of indicia bearing cards, means on the platform for transferring said cards from one group to another, a plunger carried by the platform at each end of the latter, a portion of which lies in the path of movement of a card being transferred to intercept the latter, and yieldable means engaged with each of the plungers to retract the 120 latter after it has been urged a predetermined distance by said card transfer means.
